MOUNTING FOR INTERNAL COMBUSTION ENGINES

Hans Kremser, Bergisch-Gladbach, Germany,
assignor to Humboldt-Deutzmotoren, A. G.,
Cologne-Deutz, Germany

Application May 4, 1934, Serial No. 723,994
In Germany May 26, 1933

1 Claim. (Cl. 121—194)

The invention relates to a mounting for internal combustion engines in which several pistons in angularly displaced cylinders operate upon a common crank shaft, and more particularly for engines having a star-shaped arrangement of cylinders.

With the exception of known arrangements of radial motors in flying apparatus, in which sufficient space is provided also below the machine, the lower cylinders of such motors are not accessible for the dismantling of a piston, the grinding of the valves, or the like. For example, this is the case when the radial engine with a horizontal crank shaft is built into a conveyance such as a railway car, automobile, or boat. In such cases, as a rule, the shaft must lie as deep as possible, so that at times the lower cylinder extends below the bottom surface of the machine base. Difficulties arise particularly when the motor is supported freely by a fastening at only one end thereof, in which case, upon the loosening of the fastening means, the weight of the motor is not supported by the crank shaft. Heretofore, the motor had to be especially supported at its free end before loosening the fastening flanges or else it had to be completely dismantled.

By the instant invention, the accessibility of all of the engine cylinders is rendered easy without the necessity for a dismantling of the engine. The invention consists in the mounting of the engine in such a manner by means of a flange thereon that upon the loosening of one or more screws or bolts it may be rotated about a fastening flange therefor. In this manner one can bring successively all of the working cylinders into the most desirable positions for the necessary work thereon.

Two embodiments of the invention are illustrated in the accompanying drawing wherein

Fig. 1 shows a star-shaped motor with a marine drive in side elevation with certain parts in section,

Fig. 2 is a view similar to Fig. 1, through a multistage drive, adapted for example to an automobile or to a railway car, and

Fig. 3 is a horizontal sectional view of the drive shown in Fig. 2.

In Fig. 1, a four-cylinder star-shaped motor is freely extended from the housing 2 of the reversing gear. The crank shaft 4 carries on its left end the cooling fan 3. The shaft is supported at its right end in ball bearings 5 which are disposed in the motor casing. Upon the outermost right end of the crank shaft is mounted a driving pinion 6 which engages with the gear

wheel 7. The reversing drive is of the known type. The drive is executed either directly from gear wheel 7 to the cage 8 and the slip clutch 9 onto the tail shaft 10, or over the bevel gear 11, intermediate gear wheels 12, and the bevel gear 13 which is keyed onto the tail shaft 10. For this purpose, in the former case, the clutch 9, controlled by reversing lever 14, is shifted into operation by means of the ring 15 and the roller levers 16; in the latter case the clutch is released and the brake band 17 is pulled tight to hold the cage 8. The tail shaft 10 is fitted with water-tight connections in the stern tube 18 which is led through the boat wall. The tail shaft carries at its outermost end the screw propeller 19.

The engine housing has a flange 20 which is disposed between the end wall of the drive housing and a ring 21 which is fastened thereon by means of screws or bolts 22. The housings are thus exactly centered with respect to each other. When the fastening ring 21 is pulled tight, the flange 20 may still be rotated. In operation of the machine, relative rotation is prevented by means of a fitting in the form of a bolt 23, which is screwed into the ring 21 and furthermore engages in the flange 20 with a cylindrical end. In order to effect a rotation of the engine it is simply necessary to screw out the bolt 23.

The engine is designed as a high speed machine. The reduction in speed by means of the gear wheels 6 and 7 is so chosen that the motor is elevated with respect to the reversing gear, and the lower boundary of the motor and the drive is at approximately the same elevation. The mounting of the motor in accordance with the invention is in this case especially advantageous because the motor housing cannot be supported by the crank shaft after the loosening of the mounting means.

The assembly of the motor and driving arrangement in Figs. 2 and 3 is shown with two longitudinal edges 24, each supported upon a carrier 25. The line 26 designates a depression of the type into which extend the driving gear and the lower portion of the motor. This line 26 corresponds to the lower boundary of the space for the machine in an automobile or railway car. The elements in this arrangement corresponding to those shown in Fig. 1 are designated with the same reference characters. A fastening ring 21 is disposed upon a circular flange 20 on the engine casing, which ring is fastened onto the housing 27 of the multi-stage drive by means of screw bolts 22. The flange 20 is provided upon its opposite sides with a frictional covering 55

which prevents a rotation of the engine in the course of operation thereof. The ring 21 is pressed tight against the flange 20 by means of the screws 22, a slight clearance preferably being provided between the ring 21 and the housing 27 even when the screws 22 are in tightened position. When the motor is at rest and a turning of the casing thereof is desired, it is merely necessary to loosen all of the screws 22 without 10 completely removing them.

5 The crankshaft 4 carries at its right end a clutch disk 29. The complementary disk 30 of the clutch is maintained in engagement with the disk 29 by means of a spiral spring 31. The disk 29 may be shifted out of operation in the usual manner by means of a lever, which is not shown. Upon the shaft 32 are provided three 15 loosely rotatable gear wheels of different sizes 33, 34, 35, which alternatively may be rigidly coupled 20 with the shaft 32 by means of clutches 36, 37.

and 38, respectively. Thereby one of the gear wheels 33, 40 and 41, which are keyed upon the driven shaft 42, may be selectively actuated.

Having described my invention,

I claim:—

5 In an apparatus of the class described, an internal combustion engine comprising a casing, radially disposed cylinders, and a crank shaft; a base for said engine at one end thereof; and fastening means between said engine and said 10 base comprising a circular flange on said casing, a fastening ring for retaining said flange adjacent said base whereby said engine is supported for rotation about the axis of said crank shaft, and at least one bolt member detachably engaging 15 said flange for preventing rotation of said flange and engine in the course of operation of the latter.

HANS KREMSE. 20
